UNITED STATES PATENT OFFICE.

THOMAS G. THOMPSON, OF OSWEGO, NEW YORK.

IMPROVED TOOL FOR MAKING HORSESHOES.

Specification forming part of Letters Patent No. 59,479, dated November 6, 1866.

To all whom it may concern:

Be it known that I, THOMAS G. THOMPSON of the city of Oswego, in the county of Oswego, and State of New York, have invented a new and useful machine for holding horseshoes to their place against a blacksmith's anvil while sharpening the calks thereof; and I do hereby declare that the following is a full, clear, and exact description of the construction and operation of the same, reference being had to the annexed drawings, making a part of this specification, in which—

Figure 1 is a perspective view, and Fig. 2 a longitudinal elevation.

No. 1 represents a steel spring; 2, a chain connecting the spring and lever; 3, steel point for pressing the shoe against the anvil; 4, anvil; 5, lever worked with the foot; 6, slide for the lever to work in; 7, bolt or fulerum which fastens the end of the lever to the block; 8, end of the lever for the foot of the workman, by pressing on which the point 3 is brought and held against the shoe at the anvil; 9, wooden block on which the anvil rests; 10, point at which the chain is attached to the

spring; 11, screw fastening the spring to the block.

The lever 5 is on the side of the anvil where the workman stands, fronting the forge, and the spring 1 is on the opposite or back side of the anvil. The shoe is placed against the back side of the anvil, the calk to be sharpened resting on the top of the anvil, in front of the steel point 3. The workman then places his foot on the end of the lever 8 and bears part of his weight upon it, when the point 3 is brought up against the shoe and holds it in its place while the calk is being sharpened. The chain 2 passes through the wooden block along a hole large enough to allow the chain to move freely back and forth.

I claim—

The combination of the spring-holder, chain, and foot-lever with the anvil-block and anvil, all constructed and arranged as and for the purpose described.

THOMAS G. THOMPSON.
